ENGINE AFTERBURNER CONTROL SYSTEM
Charles W. Morris, 11769 Chenault St.,
Los Angeles 49, Calif.
Filed Feb. 21, 1961, Ser. No. 90,675
3 Claims. (Cl. 60—29)

In general this invention relates to a means and method for insuring proper operation of spark-ignited combustion chambers which treat the exhaust gases of internal combustion engines. Such chambers are commonly referred to as afterburners. More specifically, this invention involves a new form of a dual insulated electrode spark plug adapted for use in an afterburner or other device. When used in an afterburner, the proper operation of such sparkplug controls the ignition system of the internal combustion engine whose exhaust gases are treated by said after burner.

It is generally known that the exhaust gases of internal combustion engines contain substantial amounts of hydrocarbons, carbon monoxide, oxides of nitrogen and other noxious components which contaminate the surrounding air. In metropolitan areas, due to the very large number of internal combustion engines being used in cars, trucks and buses in a relatively small area, the atmospheric pollution from this source alone reaches relatively high concentrations. Such atmospheric contamination, popularly known as smog, has serious detrimental effects upon the health of the population, animals and vegetation in such areas. These effects have resulted in large expenditures of time and money directed to the elimination of smog, but to date the control of smog from the exhaust of internal combustion engines has been prohibitively expensive.

It is now generally known that the primary source of smog is the unburned hydrocarbon and carbon-monoxide content of exhaust gases. Consequently much effort has been directed toward completion of the combustion process by passing the exhaust gases through a combustion chamber prior to release to the atmosphere. Such afterburners commonly utilize spark-ignited combustion analogous to the combustion in the engine because of the outstanding advantages of simplicity and economy when compared to other combustion processes such as catalytic combustion.

However, the present spark-ignited afterburners have not attained sufficient reliability to insure that once installed they will complete combustion of the exhaust gases over long periods of time under all driving conditions without frequent inspection. It must be remembered that in addition to the approximately six million new vehicles coming into service each year, there are approximately ten times that number of older vehicles already in service. During operation, these vehicles are subjected to extremely wide ranges of driving conditions. Likewise each individual vehicle is operated differently with respect to variables such as number of miles traveled each day and the number of stops and starts. Installation of an afterburner has no meaning and fails to accomplish the desired objective unless such device is actually maintained in operative condition during use of a vehicle. Periodic inspection of all vehicles has been suggested, but to set up an adequate inspection system under divergent conditions of use would require an enormously expensive and time-consuming system which would greatly complicate the solution of the smog problem.

As part of the present invention it has been found that the primary cause for malfunctioning of spark-ignited afterburners is improper sparking. At present, if the sparkplug in the afterburner is totally inoperative or producing weak, ineffective sparks, the only way to ascertain this fact is to actually inspect it by removal and testing.

2

This procedure requires just the sort of frequent and expensive inspection with its attendant problems which have already been pointed out. The present invention completely eliminates the inspection problem by making the ignition system for the internal combustion engine dependent on the proper sparking of the afterburner sparkplug. If the afterburner sparkplug is burned out, the engine fails to operate and the cause is quite simple to find. If the afterburner sparkplug is weak, the operation of the engine is markedly affected and again the cause is easy to determine.

In addition to the advantage of eliminating frequent inspections, the present invention also involves a sparkplug which greatly minimizes induction effects which impair the efficiency of sparkplugs now available for use in afterburners. The sparkplug of the present invention is simple and economical to make. Also the sparkplug of the present invention gives spark points which promote sparking and produces larger, more effective electrical discharge in the desired zone.

In general, the present invention comprises sparking means containing at least two spaced, insulated electrodes with adjacent spark points in an afterburner receiving the exhaust gases from an internal combustion engine. Preferably the sparking means comprises two non-parallel, spaced, elongated electrodes with spark points at their adjacent ends and terminals at their remote ends, with a single body of insulating material completely enclosing and separating the electrodes between the spark points and terminals. High voltage electrical impulses are supplied at regular intervals to one of said electrodes. These electrical impulses are then transmitted to another of said electrodes by sparking between the electrode spark points and then distributed to ignition means in the internal combustion engine.

One feature of the present invention is that the electrical impulses from the customary induction coil are received by one insulated electrode of the afterburner sparkplug, are transmitted to another insulated electrode of the afterburner sparkplug by sparking and then are sent to the customary distributor from the other electrode. The prior art always grounded one of the electrodes of the afterburner sparkplug so that electrical impulses sent to the afterburner sparkplug could not be further utilized and there was no way to know whether such sparkplug was operating properly short of actual removal and testing.

Another feature of the present invention is that the dual insulated electrodes are non-parallel so that any interaction between the electro-magnetic or induction fields surrounding said electrodes is minimized and consequently the resistance to current flow and decreased sparking caused be such that interaction is minimized. The reason that the interaction is minimized is that the angle between the electrodes causes the encircling electro-magnetic fields to be separated and also to contact at an angle. The metal collar which may be used to attach the sparkplug of the present invention to the afterburner is not an electrode so it does not influence the operation of the sparkplug. In addition, such spacing insures edge-to-edge spark points which increases the intensity and effectiveness of the electrical discharge between the spark points.

The prior art utilized parallel coaxial electrodes with the outer grounded electrode forming a collar around the inner electrode and with surface-to-surface spark points. Since the electro-magnetic field set up by the electrodes encircles the electrodes, the interaction between the fields in the prior art sparkplugs was at a maximum, i.e. the outer grounded electrode coincided exactly with the field set up by the inner electrode.

An object of the present invention is to insure proper

operation of spark-ignited afterburners without the necessity of frequent inspection.

Another object of the present invention is to control the ignition system of internal combustion engines through proper operation of their associated afterburner sparkplug.

Still another object of the present invention is an afterburner sparkplug which efficiently, simply and economically permits control of the ignition system of its associated internal combustion engine.

Other objects and advantages of this invention will be readily apparent from the following description and drawings which illustrate an exemplary embodiment of this invention.

In the drawings:

FIG. 1 represents a simplified schematic diagram of an internal combustion engine with its associated ignition and exhaust systems, incorporating the present invention.

FIG. 2 represents an enlarged cross-section of the afterburner sparkplug shown in FIG. 1.

FIG. 3 is a bottom view of the sparkplug shown in FIG. 2.

As shown in FIG. 1, an exemplary system employing the present invention comprises an ignition system generally indicated at 1 which controls the operation of an internal combustion engine 10 and an exhaust system generally indicated at 20 which treats the combustion products from the internal combustion engine 10. In ignition system 1, a source of low voltage such as a battery 2 is connected through a switch 3 to the primary of an induction coil 4 and an automatic switch 5, usually called a timer, which is opened at regular intervals by the operation of the engine 10. A complete electrical circuit is formed when switch 3 and timer 5 is closed so that current may flow through induction coil 4. A capacitor 6 is connected in parallel with timer 5 to absorb the energy which would otherwise cause a small arc when the contact points of timer 5 are opened. The secondary of induction coil 4 is electrically connected by lead 4' to conduct the electrical impulses caused by timer 5 and induction coil 4 to one electrode of afterburner sparkplug 7. The other electrode of afterburner sparkplug 7 is electrically connected by lead 7' to a distributor 8 to conduct thereto the electrical impulses caused by the sparking between the electrodes of sparkplug 7. Distributor 8 is in turn electrically connected to the sparkplugs 9 of internal combustion engine 10 and supplies energy to such plugs in a desired sequence and in timed relation to the rotation of the engine.

In the exhaust system 20, the exhaust gases from engine 10 are received in a manifold 21 and conducted to afterburner 22. The afterburner 22 may not only complete the combustion of the exhaust gases and reduce their hydrocarbon and monoxide content but may also muffle the explosive expansion of exhaust gases from engine 10. The exhaust gases are conducted from afterburner 22 by exhaust pipe 23 which may pass through a separate muffler if afterburner 22 does not include a muffler.

When internal combustion engine 10 is started by using a starter motor (not shown) and closing switch 3, the battery 2 sends low voltage current through induction coil 4 and timer 5 where it is broken up into electrical impulses and converted into high voltage impulses. The high voltage impulses from induction coil 4 are supplied to sparkplug 7 in afterburner 22 by means of lead 4'. These high voltage impulses are transmitted to distributor 8 through lead 7' by means of sparking between the electrodes of sparkplug 7. Distributor 8 shunts each impulse to the sparkplug in the particular cylinder ready to receive ignition action. The exhaust gases from engine 10 pass to afterburner 22 through manifold 21. In afterburner 22, the combustion of the exhaust gases is completed by ignition with sparkplug 7.

It should be noted particularly that this method of engine cylinder ignition makes such ignition wholly de-

pendent on the proper sparking of the sparkplug in the afterburner. If the afterburner sparkplug is defective in any way, the engine operation will be markedly affected so the owner of the vehicle will be forced to maintain the afterburner sparkplug in proper condition. In addition, periodic inspection becomes unnecessary since the engine operation itself affords a constant, accurate indication of whether the afterburner is operating properly. In the prior art where the afterburner sparkplug was grounded and the engine operated independently of it, periodic inspection was necessary and even then the sparkplug could fail shortly after inspection and permit smog discharge until the next inspection.

In FIGS. 2 and 3, an afterburner sparkplug 7 of the character adapted for use in the system shown in FIG. 1, is shown in great detail. Electrodes 30 and 30' are spaced and set at an angle to each other so that their spark points 31 and 31' are adjacent while their terminals 32 and 32', which are connected to leads 4' and 7' respectively, are remote. Electrodes 30 and 30' are preferably completely enclosed and separated by a single body of insulating material 33 between their spark points and terminals. Ceramic compositions resistant to high temperatures and high temperature gradients, and having good dielectric properties are generally employed for the sparkplug bodies. A spacing extension 33' from insulator 33 insures insulation between terminals 32 and 32'. The annular ridge extension 33" from the insulator 33 forms a seat for an annular metal collar 34 which surrounds insulator 33 adjacent the electrode spark points 31 and 31'. Collar 34 is clamped by a flanged ring 35 to ridge extension 33" and externally threaded to facilitate attachment of sparkplug 7 to afterburner 22.

In general, the sparkplug of the present invention may be made of the same materials presently used to make the sparkplugs which are already well known in the prior art. The spark gap between the insulated electrodes of the sparkplug will vary depending on the nature of the gaseous mixture in the afterburner to be ignited but usually will be considerably greater than those presently used in sparkplugs in the internal combustion engine. The angle between the insulated electrodes of the sparkplug may vary depending on the relative importance of reducing the resistance to current flow in the electrodes and makes the sparkplug compact. As the angle between the electrodes is increased, the interaction between the electro-magnetic fields surrounding said electrodes is decreased but the sparkplug itself becomes larger. In general it is preferred that the angle be from 10° to 30°, most preferably about 20°.

The present invention is subject to many modifications and variations. For example, a magneto system may replace the battery and coil system as a source of high voltage electrical impulses to the afterburner sparkplug. Also, although the invention has been exemplified by using a single, dual insulated electrode sparkplug in the afterburner, several of such sparkplugs may be used. In addition, each sparkplug may have more than two insulated electrodes.

As exemplified, the non-parallel, dual insulated electrodes of the sparkplug of the present invention lie in the same plane. However, such electrodes may be skew as long as they are enclosed in a single body of insulating material and encircled by a single metal collar.

The foregoing description and examples are only illustrative of the present invention and are not limitations on its scope. All alterations, modifications and variations of the present invention which are obvious to those skilled in the art or come within the scope of the following claims are considered as part of the present invention.

I claim:

1. In combination with a multi-cylinder internal combustion engine including an ignition system and a spark-ignited afterburner receiving the exhaust gases from said engine the provision of: a sparkplug inserted in said afterburner containing two spaced insulated electrodes

with adjacent spark points; means operatively connected to one of said electrodes for supplying at regular intervals high voltage electrical impulses; and means operatively connected to the other of said electrodes for distributing said electrical impulses in set sequence to ignition means in the engine cylinders whereby operation of said internal combustion engine is controlled by the proper sparking of the afterburner sparkplug so that the need for frequent inspection of said afterburner is eliminated.

2. In combination with an internal combustion engine including an ignition system and a spark-ignited afterburner receiving the exhaust gases from said engine the provision of: sparking means in said afterburner comprising at least two spaced insulated electrodes with adjacent spark points; means operatively connected to at least one of said electrodes for supplying at regular intervals high voltage electrical impulses; and means operatively connected to at least one other of said electrodes, for distributing said electrical impulses to ignition means in the internal combustion engine; whereby operation of said internal combustion engine is controlled by the proper sparking of the afterburner sparkplug so that the need for frequent inspection of said afterburner is eliminated.

3. In combination with a multi-cylinder internal combustion engine, including an ignition system and a spark-

ignited afterburner receiving the exhaust gases from said engine, the provision of: a sparkplug inserted in said afterburner comprising two non-parallel, spaced, elongated electrodes with spark points at their adjacent ends and terminals at their remote ends and a single body of insulating material completely enclosing and separating said electrodes between said spark points and said terminals; means operatively connected to the terminal of one of said electrodes for supplying at regular intervals high voltage electrical impulses; and means operatively connected to the terminal of the other of said electrodes for distributing said electrical impulses in set sequence to the ignition means in the engine cylinders whereby operation of said internal combustion engine is controlled by the proper sparking of the afterburner sparkplug so that the need for frequent inspection of said afterburner is eliminated.
